DISPENSING DEVICE

John G. Erickson and Sidney Graham,
Prescott, Ariz.

Application May 15, 1940, Serial No. 335,418

3 Claims. (Cl. 221—60)

The present invention relates to new and useful improvements in dispensing devices particularly for toothpaste, shaving cream, etc., in collapsible tubes or containers and has for its primary object to provide, in a manner as herein-after set forth, a device of this character embodying novel means whereby substantially all of the material may be conveniently ejected from the collapsible tube or container in a neat, sanitary manner.

Another very important object of the invention is to provide a dispensing device of the aforementioned character comprising novel means for capping and uncapping the collapsible tube or container.

Other objects of the invention are to provide a dispensing device of the character described which will be comparatively simple in construction, strong, durable, highly efficient and reliable in use, compact, light in weight, attractive in appearance and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a top plan view of a dispensing device constructed in accordance with the present invention.

Figure 2 is a bottom plan view of the device.

Figure 3 is a top plan view, showing the casing open.

Figure 4 is a view in vertical longitudinal section, taken substantially on the line 4—4 of Fig. 1.

Figure 5 is a view in side elevation of the device, showing the cap in open position.

Figure 6 is a cross sectional view, taken substantially on the line 6—6 of Fig. 4.

Figure 7 is a view in front elevation of the device.

Referring now to the drawings in detail, it will be seen that the embodiment of the invention which has been illustrated comprises an elongated casing 1 of suitable metal, said casing being of the cross sectional shape shown to advantage in Fig. 6 of the drawings. The longitudinal edges of the casing 1 are provided with integral, inturned flanges 2. The upper portion of the casing 1 has formed therein, at an intermediate point, a longitudinal slot 3 the purpose of which will be presently set forth. It will be observed

that the casing 1 is open at its bottom. The reference numeral 4 designates a closure of arcuate cross section for the bottom of the casing 1, said closure being hingedly mounted on one side of said casing, as at 5. On the free end of the closure 4 is a resilient latch 6 which is engageable with the casing 1 for releasably securing said closure in closed position thereon. It will be noted that the latch 6 extends the length of the closure 4.

Mounted longitudinally in the casing 1 on opposite sides of the slot 3 are spaced, parallel lining segments 7 of suitable metal. The lining segments 7 extend to the front and rear ends 8 and 9, respectively, of the casing 1. Mounted for reciprocation in the casing 1, between the lining segments 7, is a manually operable rack bar 10. An actuating knob or handle 11 for the rack bar 10 is operable in the slot 3.

Mounted for longitudinal movement in the casing 1 is an ejector which is designated by the reference numeral 12. The ejector 12 includes a substantially U-shaped frame 13 of suitable metal having mounted transversely therein supporting pins or shafts 14 and 15. Referring again to Fig. 6 of the drawings, it will be noted that the end portions of the shafts 14 and 15 project beyond the sides of the frame 13 and are engaged between the flanges 2 on the casing 1 and the adjacent longitudinal edges of the lining segments 7. Thus, the ejector 12 is supported for longitudinal movement in the casing 1.

The ejector 12 further includes a substantially bulbous tube squeezing roller 16 which is mounted on the shaft 15 in the frame 13. Mounted longitudinally on top of the frame 13 is a rearwardly directed resilient pawl 17 which is operatively engaged with the rack bar 10 for actuation thereby. A thumb lever 18 is fixed on the free end portion of the pawl 17 for disengaging said pawl from the rack bar 10 when it is desired to retract the ejector 12. A notch or recess 19 (see Fig. 3) in the rear end portion of the frame 13 accommodates the thumb lever 18.

The reference numeral 20 designates a conventional collapsible tube mounted in the dispenser, said tube resting in the closure 4. The forward end wall 8 and the corresponding end wall 21 of the closure 4 have formed therein complementary notches or recesses which, in conjunction with each other, define a circular opening 22 which accommodates the neck 23 of the tube 20. Projecting forwardly from the closure 4 are bearings 24 between which a cap 25 is journaled for swinging movement. Of course, the cap 25 is en-

gageable with the neck 23 for closing the collapsible tube 20. The pivot of the cap 25 has fixed thereon a gear 26'. The closure 4 is provided with a longitudinally extending guide 27. Slidable in the guide 27 is a metallic bar or strip 28 having rack teeth 29 on its forward end portion engaged with the gear 26' for opening and closing the cap 25. A thumb piece or button 30 is provided on the forward portion of the bar 26 for actuating same.

It is thought that the operation of the device will be readily apparent from a consideration of the foregoing. Briefly, with the rack bar 10 and the ejector 12 in fully retracted position, the collapsible tube 20 is placed in the device with the neck 23 projecting through the opening 22. The rack bar 26 is then moved forwardly for closing the cap 25 on the neck 23. To dispense the paste, cream or other material in the tube 20, the rack bar 26 is moved inwardly or rearwardly for swinging the cap 25 to open position, as seen in Fig. 5 of the drawings. Then, the rack bar 10 is moved forwardly through the medium of the handle or button 11 traveling in the slot 3. Thus, the ejector 12 is moved forwardly by reason of the fact that the pawl 17 is engaged with the rack bar 10. In this manner the collapsible tube 20 is squeezed between the roller 16 and the closure 4 for ejecting the paste or cream. For the next stroke the rack bar 10 is retracted, during which operation the resilient pawl 17 rides over the teeth of said rack bar. The rack bar 10 is again moved forwardly for actuating the ejector 12. This operation is repeated until the collapsible tube is substantially empty. When a full tube is to be placed in the device the ejector 12 may be retracted by disengaging the resilient pawl 17 from the rack bar 10 through the medium of the thumb lever 18. As seen in Fig. 6 of the drawings, the rack bar 10 is provided with longitudinal side flanges which are slidably engaged between the adjacent marginal portions of the lining segments 7 and the casing 1.

It is believed that the many advantages of a dispenser constructed in accordance with the present invention will be readily understood and although a preferred embodiment of the device is as illustrated and described, it is to be understood that changes in the details of construction and in the combination and arrangement of parts may be resorted to which will fall within the scope of the invention as claimed.

What is claimed is:

1. A dispensing device comprising a casing for the reception of a collapsible tube, a rack bar mounted for reciprocation in the casing, and an ejector slidably mounted in the casing, said ejector including a substantially U-shaped frame, a squeezing roller journaled in said frame and engageable with the tube, a resilient pawl on the right portion of the frame and engaged with the rack bar for connecting the ejector thereto for actuation thereby in a step by step manner, and a thumb lever fixed on the pawl for disengaging said pawl from the rack bar.

2. A dispensing device comprising a casing for the reception of a collapsible tube, inturned flanges on said casing, lining segments mounted in the casing and spaced from each other and from the flanges, a manually operable rack bar mounted for reciprocation in the casing between the lining segments, and an ejector mounted for operation in the casing, said ejector including a frame, shafts traversing said frame and having their end portions engaged between the lining segments and the flanges for supporting said frame, a squeezing roller on one of the shafts engageable with the tube, and a pawl mounted on the frame and engaged with the rack bar for operatively connecting the ejector thereto for actuation thereby in a step by step fashion.

3. A dispensing device comprising an elongated casing, a cover hingedly mounted on said casing, the casing for the reception of a collapsible tube, spaced lining segments mounted longitudinally in the casing, a manually operable rack bar slidably mounted in the casing between the lining segments, inturned flanges on the casing spaced from the lining segments and parallel therewith, and an ejector operable in the casing, said ejector including a substantially U-shaped frame, shafts traversing said frame and having their end portions slidably engaged between the lining segments and the flanges for supporting said frame, a roller on one of said shafts engageable with the tube for squeezing said tube against the closure, a resilient pawl on the frame engaged with the rack bar for connecting the ejector thereto for actuation thereby in a step-by-step fashion, and a thumb lever fixed on said pawl for disengaging same from the rack bar for retracting the ejector.

JOHN G. ERICKSON.
SIDNEY GRAHAM.
